(57) CLAIM

The ornamental design for a shoe bag, as shown and described.

DESCRIPTION

FIG. 1 is a perspective view of a shoe bag showing my new design;

FIG. 2 is a front elevational view thereof;

FIG. 3 is a top plan view thereof;

FIG. 4 is a right-side elevational view thereof;

FIG. 5 is a left-side elevational view thereof;

FIG. 6 is a bottom plan view thereof;

FIG. 7 is a rear elevational view thereof; and,

FIG. 8 is a perspective view depicting shoes contained within the shoe bag.

The dashed lines in FIG. 8 are included for purposes of illustrating a pair of shoes disposed in the shoe bag and form no part of the claimed design.
